UNITED STATES PATENT OFFICE

ALFRED G. F. KUROWSKI, OF BROOKLYN, NEW YORK, ASSIGNOR TO UNDERWOOD ELLIOTT FISHER COMPANY, OF NEW YORK, N. Y., A CORPORATION OF DELAWARE

TYPEWRITING MACHINE

Application filed May 23, 1929. Serial No. 365,276.

This invention relates to typewriting and like machines, and more particularly to the tabulating mechanism of such machines.

When the tabulator-key of an Underwood typewriter is depressed, the carriage is released and travels to a desired point, being brought to a standstill by stops which are brought into effective position by the depression of said key.

10 The tabulator-frame and the stops carried thereby, being at the rear of the typewriter and obstructed from the view of the typist, it is usually necessary to rise to look at the scale on the tabulator-frame in order to correctly set the tabulator-stops. This method is tedious, slow and unsatisfactory, and sometimes results in the stops being improperly placed.

It is therefore an object of the present invention to provide a device which will eliminate the mentioned procedure and enable the typist to quickly and accurately set the tabulator-stops while seated and without seeing them.

25 Another object is the provision of means for locking the carriage to the tabulator-frame while a stop is being set, so that the carriage may not be accidentally displaced from the position in which it has been set for indicating the proper position of a stop.

A further object looks to mechanism by which stops may be set without reference to a scale.

30 A feature of the invention is an arrangement whereby the setting of a stop unlocks the carriage, leaving it free for typing action, or for a resetting to indicate where another stop is to be placed.

Other features and advantages will herein-after appear.

In the accompanying drawings,

35 Figure 1 is a perspective view of a rear portion of a typewriter, including tabulating mechanism and the device of my invention, as applied thereto.

Figure 2 is an enlarged perspective view of the middle portion of Figure 1.

Figure 3 is an elevational view of the essential elements shown in Figure 2.

40 Figure 4 is a sectional side view of a type-

writer, including tabulating mechanism, only such parts being shown as are necessary to illustrate the present invention.

Figure 5 is a sectional side view of a portion of the tabulating mechanism, showing a tabulator-stop disengaging a guide from the stop-bar.

Figure 6 is a view similar to Figure 5, showing the guide in disengaged position and a stop engaging the stop-bar.

45 Referring to the drawings, a type-bar 1 is swingable upwardly towards a sheet of paper 1^a positioned against a side gage 1^b and on a platen 2 mounted in a platen-frame 3 on a carriage 4, which is in a carriage-frame 5, the carriage being provided with a pointer 4^a placed over a scale 4^b on the machine-frame. The carriage rides upon parallel rails 6, and is urged in a letter-feeding and tabulating direction by a spring-motor 7, to which the carriage is connected by means of a strap 8. The usual escapement-mechanism for letter-feeding includes a universal bar 9 actuatable in the usual manner by a heel of any type-bar. A rearward extension 9^a of the universal bar engages a dog-rocker 10 and causes the dog-rocker to vibrate upon each stroke of a type-key. The dog-rocker is pivoted at 9^b and has thereon, besides a fixed dog 11, a loose dog 12. These dogs co-operate with an escapement-wheel 13, to which is fastened, by means of the usual one-way driving connection, a pinion 13^a. The pinion meshes with a letter-feeding rack 13^b mounted on arms 14 and pivoted to the sides of the typewriter-carriage.

50 The usual column tabulator-frame 15 is pivotally supported at its ends on a typewriter-frame 17 by pivot-screws 18. The column tabulator-frame 15 includes a rack or stop bar 20 having a scale 21 marked thereon and a circular rod 22, the latter carrying slideable column tabulator-stops 23 rotatably movable into and out of interlocking engagement with the rack-bar and having handles 23^a.

55 The lower portion of the rack-bar, which is also known by the terms tabulator-bar, tabulator-rack and stop-bar, has a rack formation of spaced teeth 25 and interdental spaces 100

27, the latter accommodating tenons 28 formed on the stops 23. The stops 23 are in effective or operative position to limit the movement of the carriage when they are in engagement with the rack-bar 20, and are brought into the path of a carriage-detent 30 formed on the bottom of a plate 31 which is affixed to a portion 32 of the carriage 4 by screws 33. The stops 23 may be brought into the path of the detent 30 by rocking the tabulator-frame to advance it from the backwardly-inclined portion shown in Figure 1 to a substantially vertical position, this movement being accomplished by striking a tabulator-key 37, shown in Figure 4. The depression of the key 37 is effective to rock forwardly the tabulator-frame 15, through the action of a key-lever 38, a vertically-disposed draw-link 40 and a member 41 which is rigidly connected to the frame, the draw-link being pivotally connected to the key-lever 38 and the member 41 at its lower and upper ends, respectively.

Well-known mechanism on the Underwood typewriter is provided, whereby the forward rocking motion of the tabulator-frame releases the carriage for free movement, permitting it to move until the detent 30 comes against a stop 23, which has been thrown into its path by the forward movement of the tabulator-frame.

The means provided for quickly and accurately setting a column tabulator-stop 23 includes an arcuate guide, tooth or stop position finder 45 which may be moved into, and out of, co-operative relation with the stop-bar 20 to limit the movement of the stop 23 as the latter is moved along its supporting rod 22. Secured to the guide is a pointer 21^a positioned over the scale 21. The guide may be thrown into locking engagement with the rack-bar 20, its free end entering an interdental space 27, and, to provide for such movement, it is pivotally mounted on a pivot-pin 46 which is carried by a bracket 47 formed as an extension of the plate 31 fast to the carriage. The guide thus travels with the carriage, and, when in engagement with the rack-bar 20, locks the carriage and prevents it from accidental displacement while a stop 23 is being moved against the guide.

A V-shaped spring 49, secured to the bracket 47 by screws 50, is provided to hold the guide 45 in or out of engagement with the stop-bar, as the case may be. The spring contacts with a pin 52 which is fixed to, and extends outwardly from, the guide 45, the lower inclined portion of the spring functioning to hold the guide in engagement with the rack-bar, as shown in Figures 1 and 2, and the upper inclined portion acting to hold the guide out of engagement with the same. The pin 46, on which the guide is mounted, extends through a slot 54 in the spring 49 to give added support to the latter.

When a stop 23 has been moved along the rod 22 until it abuts the guide 45, it is swung into engagement with the rack or stop bar, and, in that movement, a member 55, secured to the stop, is pushed against a narrow ledge 56 extending from the guide, as shown in Figure 5, and thus withdraws the guide from engagement with the rack-bar and lifts it to the position shown in Figure 6, in which position it is held by the spring 49. The width of the ledge 56 is preferably not greater than the width of a tooth 25, so that a stop will not disengage the guide from the stop-bar unless the stop contacts the guide, whereby the carriage remains locked until the stop is correctly positioned. In other words, if the typist attempts to proceed after incorrectly positioning a stop, the machine will not function, and the operator is apprised that the stop is not in its proper place. The disengagement of the guide from the rack or stop bar leaves the carriage free for movement if typing is to be done after setting one stop, or free to be moved to another position if another stop is to be set in the stop-bar.

Where it is desired to type on sheets having columns, the tabulator-stops, being first moved over to the extreme left of the carrying rod 22, may be set in the following manner. The usual side-edge gage 1^b may be first positioned to where the left edges of the sheets are to come. The sheets are then inserted into the machine against the side-edge gage. The carriage is then moved to the right until the extreme left-hand line on the sheet, which indicates the beginning of the second column, is brought to the printing point, the first column being automatically positioned by the carriage return, and then the novel guide 45 is swung down to effective position to thereby lock the carriage in the set position. A column-stop is then slid along its carrying rod 22 against the guide and swung into locking engagement with the stop-bar 20, which swinging operation simultaneously releases the guide. The carriage is then moved towards the left until the second vertical line or the beginning of the third column is brought to the typing position, and then the guide 45 is again moved to locking position with the stop-bar and a tabulator-stop set, the carriage then being moved further to the left to bring the third vertical line into the typing position, so that another tabulator-stop may be set, and so on until all the tabulator-stops are set for the various columns.

It will be noted that when the carriage is positioned at a stop-setting position, the depression of the stop-position finder locks the carriage against displacement, and the correct setting of the stop upon the rack automatically releases the carriage from its interlock with the finder. Hence, the column-stop cannot be set at a position indicated by the finder without releasing the carriage from

the interlock, and the carriage will not be released if the stop is incorrectly set at any other position not predetermined by the finder, and as the carriage cannot accidentally or otherwise be shifted either way after the depression of the finder, and cannot be released except by the correct setting of a stop, the operation of setting the stops along the tabulator-bar from the front of the machine is absolutely error-proof; and that the tooth is manually settable to either a rack-locking position or a rack-releasing position independently of the setting of the stop.

Variations may be resorted to within the scope of the invention, and portions of the improvements may be used without others.

Having thus described my invention, I claim:

1. In a typewriting machine, the combination with a movable carriage and a non-traveling rack, of a column-stop adjustable upon the rack, and a tooth on the carriage, movable into mesh with the rack to detain the carriage, said tooth being normally out of the path of said column-stop, but serving as a position-finder to arrest and locate said stop when the tooth is in mesh with the rack.

2. In a typewriting machine, the combination with a movable carriage and a non-traveling rack, of a column-stop adjustable upon the rack, and a tooth on the carriage, movable into mesh with the rack to detain the carriage, said tooth being normally out of the path of said column-stop, but serving as a position-finder to arrest and locate said stop when the tooth is in mesh with the rack, said tooth having means for holding it in mechanical interlock with the rack.

3. In a typewriting machine, the combination with a movable carriage and a non-traveling rack, of a column-stop adjustable upon the rack, a tooth on the carriage, movable into mesh with the rack to detain the carriage, said tooth being normally out of the path of said column-stop, but serving as a position-finder to arrest and locate said stop when the tooth is in mesh with the rack, said tooth having means for holding it in mechanical interlock with the rack, and means movable with the stop when being set upon the rack and engageable with the tooth to break the interlock of the tooth with the rack and release the carriage.

4. In a typewriting machine, the combination with a movable carriage and a non-traveling rack, of a column-stop adjustable upon the rack, a tooth on the carriage, movable into mesh with the rack to detain the carriage, said tooth normally out of the path of said column-stop, but serving as a position-finder to arrest and locate said stop when the tooth is in mesh with the rack, said tooth having means for holding it in mechanical interlock with the rack, and camming means on the stop, operable when the stop is posi-

tioned against the finder and set upon the rack, to engage means on the tooth and forcibly disengage the tooth from the rack to release the carriage.

5. In a typewriting machine, the combination with a movable carriage and a non-traveling rack, of a column-stop adjustable upon the rack, a tooth on the carriage, movable into mesh with the rack to detain the carriage, said tooth normally out of the path of said column-stop, but serving as a position-finder to arrest and locate said stop when the tooth is in mesh with the rack, said tooth having means for holding it in mechanical interlock with the rack, and camming means on the stop, operable when the stop is positioned against the finder and set upon the rack, to engage means on the tooth and forcibly disengage the tooth from the rack to release the carriage, the camming means on the stop having a co-operative tooth-engagement of less than a rack-tooth space, so that the cam becomes ineffective to cam the tooth and release the carriage, if the stop is not set upon the rack at the exact position predetermined by the rack-locking tooth.

6. In a typewriting machine having a carriage, the combination with a rack and a tabulator-stop adjustable along said rack to be moved into and out of interlock with the teeth at different points, of a guide on the carriage, movable into and out of interlock with the teeth of said rack to lock the carriage at a stop-setting position, and means on said stop, operable as the stop interlocks with said rack, to force said guide out of interlock with said rack to release the carriage.

7. In a typewriting machine having a carriage, the combination with a rack and a tabulator-stop adjustable upon said rack to be moved into and out of interlock with the teeth, of a guide on the carriage, movable into and out of interlock with said rack to lock the carriage at a stop-setting position, means operable as the stop moves into interlock with said rack, to move said guide out of interlock with said rack, and a single detent, operable to hold said guide in or out of interlock with said rack.

8. In a typewriting machine having a carriage, the combination with a stop-bar and a tabulator-stop movable into and out of engagement with said bar, of a guide for said stop, said guide being mounted on the carriage and movable into and out of co-operative relation with said bar to aid in positioning said stop, and means movable by said stop as the latter moves into engagement with said bar to move said guide out of co-operative relation with said bar.

9. In a typewriting machine having a carriage, the combination with a stop-bar and a tabulator-stop movable into and out of engagement with said bar, of a guide for said stop, said guide being pivotally mounted on

the carriage and movable into and out of co-operative relation with said bar to aid in positioning said stop, means movable by said stop as the latter moves into engagement with said bar to move said guide out of co-operative relation with said bar, and spring-means for holding said guide in or out of engagement with said bar.

10. In a typewriting machine having a carriage, the combination with a stop-bar and a tabulator-stop movable into and out of engagement with said bar at different points, of a guide on the carriage movable into and out of co-operative relation with said bar to aid in positioning said stop, means movable by said stop as the latter moves into engagement with said bar to move said guide out of co-operative relation with said bar, and a two-position detent on the carriage, operable to hold said guide in or out of engagement with said bar.

11. In a typewriting machine having a traveling carriage, the combination with a non-traveling rack having a tabulator-stop settable thereon, of a guide on the carriage, operable to interlock with the bar to lock the carriage and guide the setting of the stop upon the rack, and means on the guide, actuatable by said stop only when the stop engages with the guide, for unlocking said carriage.
